UNITED STATES PATENT OFFICE.

TEMPEL L. KINNE, OF DALLAS, TEXAS.

COTTON COMBER AND CLEANER.

Application filed November 3, 1925. Serial No. 66,654.

This invention relates to new and useful improvements in cotton gin machinery and in such connection it relates more particularly to a means whereby the cotton may be subjected to a combing and cleaning, or reginning process.

The present invention is a continuation in part of an application for patent filed April 1, 1920, Serial No. 370,483, for cotton comb-10 er and cleaner.

In cotton ginning a considerable amount of cotton falls to the floor in the process of ginning and pressing. Such cotton is gathered up and baled and contains the dirt and 15 trash from the gin floor and is otherwise tangled and lumpy.

In the process of treating such cotton, or reginning it, the usual form of gin saw is used which consists of a plurality of saws spaced apart and comprising a saw cylinder 20 with spaces between the saws, or such saws are arranged so as to give a spiral action against the cotton, and are also arranged so that the saws will have a reciprocating motion, the object of such spiral and reciprocal 25 action being to overcome or utilize the spaces of the saws arranged in spaced relationship on the shaft comprising the saw cylinder.

It is the principal object of my invention 30 to provide a saw cylinder whereon the teeth are so arranged that all available space of the cylinder is utilized against the cotton, and providing means for adjustably feeding the cotton to the cylinder, also to provide a cylinder in removable sections for convenience in repairing the cylinder, the worn or damaged part being thus adaptable to removal without replacing a completely new cylinder.

Another important object of the invention 40 is to provide a plurality of feeder-disks arranged on a shaft and provided with means for spacing the disks thereon.

A further and important object of the invention is to provide a means for controlling the feed drive by a belt tightener and unique arrangement of gears hereinafter referred to.

A final object of the invention is to provide an air blast arrangement for conveying away the dirt and trash from the cotton.

With the foregoing objects in view the invention will be better understood by reference to the following description, taken in

connection with the accompanying drawings 55 forming part hereof, and in which:

Figure 1 is a sectional view of a portion of a cotton gin wherein are embodied the main features of the invention.

Figure 2 is a side elevational view, a portion 60 of the housing being broken away.

Figure 3 is a side elevational view, partly in section and partly broken away.

Figure 4 is an enlarged detail view of the belt tightening and drive control means, 65 Figure 5 being a sectional view thereof along line 5—5 of Figure 4.

Figure 6 is a detail view of one of the feeder-disks, Figure 7 representing a spacer ring therefor.

Figure 8 is a detail view of a supporting bracket and link providing for adjustability 70 of the feeding mechanism.

Figure 9 is a fragmentary view of the toothed cylinder for combing the cotton and 75 pulling it into the machine, Figure 10 being a sectional view thereof along line 10—10 of Figure 9.

Figure 11 is a detail view of the shaft upon 80 which the feeder disks are mounted.

In carrying out the invention, there is provided a housing 1 with a hopper 2 and upper feed rollers 3—3 mounted on shaft 3^a. Each shaft carries a gear 3^b, the gears meshing one with the other. The rollers 3—3 are 85 provided with teeth 3^d. These upper rollers, however, are not claimed as a part of the invention and are described only for the sake of clearness.

Roller 4 which is of longitudinal rib formation is mounted upon a shaft 5. This shaft has its ends supported in a pair of links 9 depending from a frame 10 (only one of the links and frame being shown), clearly illustrated in Figure 8. The frame 95 10 also supports the shafts of the two upper rollers 3—3. It will be observed that a spring 12 is supported against the links 9 and has a support 13. This is for the purpose of permitting the roller 4 to move outward under pressure of the cotton when the same is fed downward from the upper rollers to relieve any undue pressure or lumps in the cotton and thus regulates the feed.

A shaft 6, of square formation along its main portion, as shown in Figure 11, has the rounded parts thereof also seated in the frame 10 at the apertures 11. Supported in

spaced relation upon the squared portion of the shaft are a plurality of saw disks 7—7. Each disk has a squared opening to fit the shaft and between each disk is a spacer ring 8. Pins 8^a hold the outer disks in place.

On the frame 10 is an arm 14 with screw 15 for adjusting purposes to bring the disk shaft 6 and roller shaft 5 to or away from the cylinder 20.

10 One end of one of the shafts 3^a carries a sprocket gear 16 and is connected by a chain drive 17 to a similar gear 18 on the shaft 6. The driving power for the sprocket gear 18 is provided for through a shaft 19 by means 15 of a belt and a pulley referred to herein-after.

On the shaft 19 is mounted a plurality of drums 20, forming a cylinder and connected together by a plurality of circular web members 21. The object of this arrangement is 20 to enable a portion of the cylinder to be repaired and replaced, without providing an entirely new cylinder. The periphery of the cylinder formed by the sections is provided with a number of teeth 22. By reference to Figures 9 and 10 it will be observed that these teeth are so arranged that they form a part of the cylinder and are set in rows so that the spaces between one row 25 are directly opposite to the teeth in the next row, the object being to utilize all the space 30 on the cylinder.

Referring now to the means employed for driving the mechanism, by reference to 35 Figures 2, 3 and 4, it will be seen that there is mounted on shaft 19 a pulley 22 and on shaft 6 beyond the gear 18 there is secured a pulley 23, the pulley and shaft being connected by a belt 24. Shaft 6 carries on one 40 end a fixed gear 25 and a loose gear 26, gear 26 having 45 teeth and its companion or inner gear 46 teeth. Both of these gears are within the pulley. The pulley has several 45 depending arms or spokes forming supports for gears 27 and 28, connected by small shafts 29.

The outer gear 26 carries a lever 30, rigidly fastened thereto. The outer end of the shaft 6 revolves slowly in the center of gear 26, the cap screw 31 being for the purpose of stabilizing the shaft and revolves loosely with the shaft through an aperture in the lever 30. The cap screw is not connected to the lever. On the lever 30 is also carried 55 a roller 32 which is advanced against the belt in the tightening movement. The shaft 19 revolved by the pulley 22 causes the belt when tightened to revolve the pulley 23. The shaft 19 revolves at approximately 500 60 revolutions per minute. The small outer gears 27 and inner gears 28 thus revolve in a planetary movement around the gears 26 and 25 due, however, to gear 25 having one more tooth than its companion 26, the small 65 gears 28 will thus move the gear 25 around

and rotate the shaft 6 at a slow rate of speed. In other words, the effect of the arrangement is somewhat similar to an effect which would be produced as if the gears 25 and 26 were connected by a chain belt—one of the gears being of slightly greater diameter, a tension is thus produced on the belt through the lever 30 and the roller 32. The additional tooth, however, provides for the movement of the shaft 6. When the lever 75 30 is moved away from the belt 24 the entire mechanism is stopped, with the exception of shaft 19.

Referring to Figure 1, the cotton on its downward movement is caught by the teeth 80 22 of the cylinder 20 and by a combing and pulling motion is dragged from the disks 7 and roller 4. The dirt and trash is thus thrown by centrifugal force into the chute 85 33 formed by the upper and lower aprons 33^a, and an air blast from an air chamber 34 carries the refuse away.

The cleaned cotton falls into a chute 35 and is conveyed away by an air blast from air chamber 36, the latter arrangement being 90 no part of this invention.

It should be understood that modifications and changes may be made in the arrangement and construction of the invention in keeping with the spirit and intent of the 95 following claims.

I claim:

1. In a machine for combing and cleaning cotton, the combination of a housing including a shaft carrying a saw cylinder, a frame consisting of a pair of plates having spaced apertures forming bearings for spaced shafts carrying feed rollers and apertures for a shaft carrying saw disks; said plates having a curved and inwardly-extended leg, adjustably fastened to the housing and including means for adjusting said leg to move the shaft of the saw disks to and from said saw cylinder; links pivotally depending from said plate and having apertures for supporting a shaft carrying an idler roller.

2. A machine as set out in claim 1, said idle roller being adapted to swing to and away from said saw cylinder by the pressure and feeding movement of the cotton downward into the machine; said links movable under spring tension.

3. An apparatus for cleaning and combing cotton comprising the combination of a casing, feeder disks on a shaft and a roller, a toothed and sectional cylinder and shaft and means for automatically adjusting the roller in the feeding of the cotton, said disk shaft carrying a fixed gear and a free gear, said gears having an unequal number of teeth and meshing with planetary revolving gears on the interior of a pulley, a lever on the free gear and a belt connecting the pulley to the shaft of said cylinder to tighten 125 130

and free the belt from connection with the cylinder shaft.

4. An apparatus for combing and cleaning cotton comprising a feeding means, a stringing and combing means, a dirt conveying means, and a drive control means, said drive control consisting of a pulley with interiorly arranged planetary gears meshing with a free gear and a gear fixed to a shaft, one of said latter gears having a greater number of teeth than the other, a belt con-

necting said pulley and a lever on the free gear for tightening the belt on the gear pulley, said planetary gears when revolved adapted to rotate loosely around the said free gear on the shaft and due to the extra teeth on said fixed gear to move or cause the shaft to rotate at a relatively slow rate of speed.

In testimony whereof I have signed my name to this specification.

TEMPEL L. KINNE.
